UNITED STATES PATENT OFFICE.

ZOLTAN GROSS AND KAROLIN GROSS, OF NEW YORK, N. Y.

FOLDING UMBRELLA.

1,187,828.

Specification of Letters Patent. Patented June 20, 1916.

Application filed September 23, 1914. Serial No. 863,120.

To all whom it may concern:

Be it known that we, ZOLTAN GROSS and KAROLIN GROSS, both citizens of the United States, and residents of New York, in the 5 county of New York and State of New York, have invented new and useful Improvements in Folding Umbrellas, of which the following is a specification.

This invention relates to folding umbrellas and has for its principal object to provide a device of this character which can be folded.

A further object of the invention is to provide a device of this character which is 15 stanch and strong, simple in construction and can speedily be made ready for use.

With the foregoing and other objects in view, the invention consists of a novel construction, combination and arrangement of 20 parts as hereinafter described and illustrated in the accompanying drawings, wherein:

Figure 1 is a perspective view of the device showing it opened, ready for use. Fig. 25 2 is an elevational view of a part of the skeleton of the umbrella, showing one detail thereof in different positions, in dotted lines. Fig. 3 is an elevational view of part 25 of the device, in folded position. Figs. 4, 5 and 6 are partly elevational, partly sectional views of different parts of the device, on an enlarged scale. Fig. 7 is a perspective detail view showing one part in alternate positions, in dotted lines. Fig. 8 is a partly elevational, partly sectional detail view. Fig. 35 9 is a side elevational view of a bag containing an umbrella constructed according to our invention, in its folded position.

The same part is designated by the same 40 reference character throughout the several views.

Referring to the drawings, 10 represents a telescopic tubular rod of three parts, 10^a, 10^b and 10^c, telescoping into each other and 45 secured in its extended position shown in the drawings, by means of spring-buttons 11 engaging corresponding holes, in the usual way.

The lowest part 10^a of the telescopic rod 50 is provided with a screw 12 projecting through its bottom and adapted to engage a handle or knob 13. At the top of the upper section 10^c of the rod is secured a crown 14 and pivoted to it are a plurality of ribs 55 15, pivoted at a short distance from their outer ends between pairs of lugs 16, forming

joint elements; also between the lugs 16 at their inner ends are rigidly engaged stretchers 17, the other ends of which are pivotally secured to a runner 18, slidably mounted on 60 the rod element 10^c as in ordinary umbrellas. Between the outer ends of the lugs 16 are pivotally connected extension ribs 19, which can be folded back on the ribs 15 parallel thereto, or swung out substantially 65 in alinement therewith. In the latter case, the end 15^a of the rib 15 is engaged by a groove 20 provided in the extension-rib 19, near its pivoted end. A ring 21 is slidably mounted on the extension rib 19 adapted to 70 be slipped over the end 15^a of the ribs 15, when lying in the groove 20, and thus secure the extension ribs in their position in alinement with the ribs 15.

A double spring-catch 22 is provided on 75 the member 10^c of the telescopic rod, in a convenient position to hold the sleeve 18 when the umbrella is open, in the usual way. It is so constructed that the part 10^b of the telescopic rod, when pushed over the spring- 80 catch 22, automatically presses it in when pushed over the part 10^c and also when pulled off same. To close the umbrella, the spring-catch 22 has to be pressed down with 85 a finger, as usual.

The above described skeleton of the umbrella is covered with a fabric 23 which is fastened to the outer ends of the extension ribs 19 and also to the ends 15^a of the ribs 15, by means of a loop. This latter prevents 90 the fabric from slipping back on the ribs 15 when the umbrella is closed.

A button or knob 24 may be applied to the top of the telescopic rod, over the fabric 23, to cover the edges thereof. We also provide a strap with a button, such as 25, for holding the umbrella together when folded, as usual, with the difference that in this device the strap is at the inside of the umbrella-cover when the umbrella is open. The 100 folded umbrella may preferably be carried in a pouch such as shown in Fig. 9.

It is understood, that while we have thus shown and described the preferred form of 105 our invention, we do not want to be limited to its mechanical details and may resort to such alterations and modifications as come within the scope of the claim hereunto appended.

We claim:

In a folding umbrella, the combination 110 with a sectional telescopic stick, a runner

slidable on the upper section thereof, a crown on the end of said stick, a plurality of ribs composed of upper and lower sections, the upper section being pivotally sections, said lower rib sections having re- 15
5 cured by one end in said crown, and corresponding stretchers similarly engaged with said runner, of joint elements rigidly engaged with the outer ends of said stretchers, said joint elements extending therebeyond, 10 pivotal connections between said joint elements near their outer ends and the upper sections of said ribs, the lower sections of said ribs being pivoted in the extensions of said joint element exteriorly of said upper

sections, said lower rib sections having recesses adapted to receive the extending ends of the upper rib sections and means for holding said upper and lower rib sections in operative engagement.

In testimony whereof, we have hereunto 20 set our signatures in the presence of two witnesses.

ZOLTAN GROSS.
KAROLIN GROSS.
